C. A. SCHELLENS & G. W. PENTHENY,
CENTRIFUGAL COMPRESSOR,
APPLICATION FILED JAN. 29, 1917.

1,250,029.

Patented Dec. 11, 1917.

UNITED STATES PATENT OFFICE.

CHRISTOPHER A. SCHELLEN, OF MARBLEHEAD, AND GEORGE W. PENTHENY, OF LYNN,
MASSACHUSETTS, ASSIGNEES TO GENERAL ELECTRIC COMPANY, A CORPORATION
OF NEW YORK.

CENTRIFUGAL COMPRESSOR.

1,250,029.

Specification of Letters Patent. Patented Dec. 11, 1917.

Application filed January 29, 1917. Serial No. 145,086.

To all whom it may concern:

Be it known that we, CHRISTOPHER A. SCHELLEN and GEORGE W. PENTHENY, citizens of the United States, residing, respectively, at Marblehead, in the county of Essex, State of Massachusetts, and at Lynn, in the county of Essex, State of Massachusetts, have invented certain new and useful Improvements in Centrifugal Compressors, 10 of which the following is a specification.

The present invention relates to centrifugal compressors, such as are designed for compressing air or other gases, or fluids, and which comprise one or more impellers 15 located within a casing, which impeller or impellers receive the fluid to be pumped on one or both sides and deliver it at the periphery.

The invention relates particularly to compressors having an impeller or impellers of the so-termed cast-in type, such an impeller comprising a plurality of suitably shaped blades around which a metal, as steel, is cast to form the hub portion and web portion 25 of the impeller, the inner ends of the blades being embedded in the cast metal to anchor them against the centrifugal stresses which are set up when the impeller rotates.

In order to reduce the centrifugal stresses 30 in the impeller, and particularly those occurring at the hub of the impeller near the bore, it is desirable to lighten the impeller as much as possible, and particularly the peripheral portion thereof where the added 35 weight of any additional metal greatly increases the centrifugal stresses in the hub, as is obvious. At the same time, it is necessary to have the impeller sufficiently strong to withstand the stresses due to centrifugal force, and the blades sufficiently 40 stiff in a transverse direction to prevent them from bending.

The object of the present invention is to provide an improved impeller of the cast- 45 in type which, while providing the necessary strength and the required stiffness of the blades will be comparatively light, particularly at its periphery.

For a consideration of what we believe to

be novel and our invention, attention is directed to the accompanying specification and the claims appended thereto.

In the accompanying drawing wherein an embodiment of the invention is illustrated, Figure 1 is an end view of a compressor, a part of the casing being broken away to show the impeller; Fig. 2 is a radial section of a portion of an impeller; Fig. 3 is a detail sectional view taken at right angles to the section of Fig. 2, and Fig. 4 is a perspective view of a blade of an impeller.

Referring to the drawing, 5 indicates a centrifugal compressor having an inlet conduit 6 and a discharge conduit 7. 8 indicates the shaft of the compressor upon which 55 is mounted the impeller, or the impellers in the case of a multi-stage compressor. The impeller comprises the blades 9, the hub 10, and the web 11, the hub having a suitable bore to receive the shaft 8. The blades 60 comprise flat radially extending plates having curved extensions which form entrance buckets 12 which extend across the outer surface of the hub and act, as is well understood, to catch the incoming fluid and direct it evenly 65 and smoothly to the spaces between the blades. The hub 10 and web 11 are cast around the inner ends of the blades to anchor them in place. The web gradually tapers in thickness toward the periphery so 70 that it gradually becomes lighter, and terminates at some distance from the periphery of the blades. The hub 10 and web 11 are curved so as to gradually change the direction of flow of the incoming fluid from an 75 axial direction to a radial one. As just stated, the web 11 terminates at some distance from the outer ends of the blades, and in order now to give the necessary stiffness 80 to the outer ends of the blades radially extending flanges or ribs 13 are provided on the blades. Preferably a single centrally located flange or rib 13 is provided on the rear side of each blade 9, the same extending 85 from the periphery thereof and having its inner end embedded in the material of the web 11. It is to be understood that by 90 the inner ends of the blades 11 and ribs or

95

flanges 13 is meant the portions of them adjacent the center of the impeller, and by the outer ends is meant the peripheral portions thereof. The flanges or ribs 13 are 5 preferably widest at a point just beyond where they enter the web 11 and gradually become narrower toward the periphery of the impeller. This gives the necessary stiffness to the blades with the least amount of 10 metal. The direction of rotation of the impeller shown is clockwise and, as will be clear, the forces tending to bend the blades back, increase from the periphery toward 15 the center. By placing the flanges or ribs 13 on the rear side of the blades the faces of the blades are left free and unobstructed.

In constructing an impeller embodying this invention, we preferably form the blades in two halves or parts 14 or 15, the 20 flange or rib 13 being made up of two sections 16 and 17, each one formed integral with each half of the blade and bent at right angles thereto. The outer ends of the sections 16 and 17 are suitably fastened together, as by rivets 18, and we may also provide one or more rivets 19; or other fastening means, in the inner ends of such sections to hold them together and in position while the hub 10 and web 11 are being 25 cast around them. In order to more firmly anchor the blades 9 and flanges 13 in the metal of the hub 10 and web 11, the blades are provided with suitable openings 19^a, and the flanges are provided with suitable openings 20 and with scalloped edges 21 into which the metal runs during the casting operation.

22 indicates wear strips riveted to the edges of the impeller blades, and 23 are 30 threaded openings adapted to receive bolts for pulling the impeller from the shaft. 24 indicates the discharge vanes of the compressor.

Fig. 4 is a perspective view of a single 35 blade with its flange before the hub and web are cast around it and before its extensions, which form the entrance buckets 12, are curved around into shape. As will be obvious, each half of the blade with its flange 40 may be readily stamped from flat sheet material, after which the flange may be bent up at right angles to the plane of the blade. This makes a very cheap and expeditious method for manufacturing the blades with 45 their attached ribs or flanges. It will be understood, however, that they may be formed in any suitable manner.

By the above described structure, wherein 50 stiffening flanges or ribs are provided for the outer ends of the blades to give them transverse stiffness, the web may be made to terminate quite some distance short of the periphery of the impeller, thus material-

ally reducing the weight of such peripheral portion, and as a consequence the stresses in 55 the hub.

In accordance with the provisions of the patent statutes, we have described the principle of operation of our invention, together with the apparatus which we now consider 70 to represent the best embodiment thereof; but we desire to have it understood that the apparatus shown is only illustrative and that the invention can be carried out by other means. 75

What we claim as new and desire to secure by Letters Patent of the United States is:

1. In an apparatus of the character described, the combination with a casing having admission and discharge openings, and a shaft, of an impeller on the shaft, comprising blades, radial flanges to stiffen the outer ends thereof, and a hub and web cast around the inner portions of the blades and 80 flanges, said web terminating short of the periphery of the blades.

2. In an apparatus of the character described, the combination with a casing having admission and discharge openings, and a 85 shaft, of an impeller on the shaft, comprising blades, and a hub and web cast around the inner portions of the blades, said web terminating short of the periphery of the blades, and flanges extending radially of 90 the blades to stiffen the outer ends thereof.

3. In an impeller, the combination of a plurality of blades having radially extending flanges for stiffening the outer ends thereof, and a hub and web cast around the 100 inner ends of said blades.

4. In an impeller, the combination of a plurality of blades having radially extending flanges, for stiffening the outer ends thereof, and a hub and web cast around the 105 inner ends of said blades, the inner ends of the flanges being embedded in the material of the web.

5. In an impeller, the combination of a plurality of blades, a hub and web cast 110 around the inner ends of the blades, said web terminating short of the periphery of the blades, and means for stiffening the outer ends of the blades comprising flanges extending radially of the blades and having 115 their inner ends embedded in the material of the web.

6. In an impeller, the combination of a plurality of blades, each comprising two parts having radially extending flanges 120 which are fastened together, and a hub and web cast around the inner ends of said blades, the inner ends of the flanges being embedded in the material of the web.

7. In an impeller, the combination of a 125 plurality of radially extending blades, a

hub and web cast about the inner ends thereof, said web terminating some distance short of the outer ends of the blades, and radial flanges formed integral with the blades on the rear sides thereof and at right angles to the plane of the blades, said flanges being located on the longitudinal axes of the

blades and having their inner ends embedded in the web.

In witness whereof, we have hereunto set our hands this 26th day of January, 1917.

CHRISTOPHER A. SCHELLENS.
GEORGE W. PENTHENY.
